UNITED STATES PATENT OFFICE

120,262

DESIGN FOR A TEXTILE FABRIC

Curt E. Forstmann, Montclair, N. J.

Application August 11, 1939, Serial No. 86,616

Term of patent 3½ years

To all whom it may concern:

Be it known that I, Curt E. Forstmann, a citizen of the United States, residing at Montclair, in the county of Essex and State of New Jersey, have invented a new, original, and ornamental Design for Textile Fabric, of which the following is a specification, reference being had to the accompanying drawing forming part thereof.

In the drawing, the sole figure is a plan view of a piece of fabric showing the design.

The fabric design embraces a series of parallel stripes of irregular outline, characterized by a fine all-over high relief stipple effect resulting from densely distributed loose loops as shown.

I claim:

The ornamental design for a textile fabric as shown and described.

CURT E. FORSTMANN.
